UNITED STATES PATENT OFFICE.

VINCENZO CONTESSA, OF BROOKLYN, NEW YORK.

DESIGN FOR A COMB.

45,739.

Specification for Design.

Patented May 12, 1914.

Application filed March 12, 1914. Serial No. 824,321. Term of patent 7 years.

To all whom it may concern:

Be it known that I, VINCENZO CONTESSA, a citizen of the United States, and residing at Brooklyn, in the county of Kings and State of New York, have invented a new, original, and ornamental Design for Combs, of which the following is a specification, reference being had to the accompanying drawing, forming part thereof.

Figure 1 is a plan view of a comb illustrating my new design, and Fig. 2 is an elevation.

I claim:—

The ornamental design for a comb, as shown.

VINCENZO CONTESSA.
